UNITED STATES PATENT OFFICE.

FREDERICK W. TOEDT, OF HAMBURG, IOWA.

COMPOUND EXPLOSIVE-ENGINE.

SPECIFICATION forming part of Letters Patent No. 691,083, dated January 14, 1902.

Application filed March 19, 1901. Serial No. 51,921. (No model.)

To all whom it may concern:

Be it known that I, FREDERICK W. TOEDT, a citizen of the United States, residing at Hamburg, in the county of Fremont and State of Iowa, have invented new and useful Improvements in Compound Explosive-Engines, of which the following is a specification.

This invention relates to certain new and useful improvements in compound explosive-engines of the four-cycle type where there is used a high-pressure and a low-pressure cylinder; and the invention consists in the construction and arrangement of the parts whereby the charge after being exploded is passed from the high-pressure cylinder to the low-pressure one to effect a second motion of the pistons and utilize the unexpended force, which usually remains unutilized, the movement being effected without a further expenditure of the explosive mixture, the momentum being imparted by the first and second impulses, the third and fourth movements clearing the cylinders of the products of combustion and drawing a charge into the high-pressure cylinder, the fourth motion also compressing the charge, as will be herein-after more fully set forth.

In the accompanying drawings, which illustrate my invention, Figure 1 is a plan view of an engine constructed in accordance with my improvement, the cylinders and one of the pistons being shown in section. Fig. 2 is a cross-section taken on the line *x* *x* of Fig. 1, and Fig. 3 is a detail view showing a modification of the port between the cylinders.

The cylinder is of the compound type and is made up to provide a high-pressure cylinder 1 and in line therewith a low-pressure cylinder 2, the high-pressure cylinder being somewhat longer than the low-pressure one to provide between its piston and its head an explosion-chamber. The high-pressure cylinder is partially surrounded by a water-chamber 3 and has on one side a way 4, which connects with the cylinder 1 by a port 5, an exit-port 6 being provided near the other end of the way 4. The cylinder-head 7 is provided with an entrance-port 8, through which the explosive mixture is admitted or drawn into the explosion-chamber by a movement of the piston of the high-pressure cylinder away

from the entrance-port. The cylinder-head may have attached thereto igniters 9 of any suitable form, and one of the wires may be in electrical contact with a moving part of the engine to make or break an electric circuit to produce in the explosion-chamber, when the explosive mixture has been compressed, a spark in order to explode the gas and give the first impulse to the piston.

The high-pressure piston 10 has a piston-rod 11, which passes through the low-pressure piston 12 and a packing-box carried thereby, the outer end of the piston-rod being suitably guided or operating between guide-bars, the rod having a pitman, which is connected to a crank 13 on the main shaft. The low-pressure piston 12 is provided with a rod or rods 14, which move between guide-bars and are connected to pitman-rods, which are attached to a crank 15, the cranks 13 and 15 being attached to the main shaft 16. Upon the shaft 16 is secured a beveled pinion 17, which meshes with a pinion 18, of such dimensions that the shaft will make two complete revolutions to one revolution of the pinion 18, which pinion carries a roller or cam 19, the function thereof being to trip at the proper time a lever 20, which is fulcrumed upon a suitable support and guided so that one end will be in the path of the roller. The lever is shown as fulcrumed upon a support 21, and its long end passes through a guide 22, a spring bearing against the guide and lever to force the lever against a stop when it is not held away therefrom by the cam or roller 19. The lever on opposite sides of the fulcrum when rocked contacts with valve-stems which carry valves for closing the ports 5 and 6, the valves being actuated in one direction by springs, the tendency of said springs being to move the valves so as to close the ports when the stems thereof are not in contact with the lever. The lever mechanism may be modified and other means substituted therefor which will properly actuate the valves without in any way changing the character of my invention.

The inlet-port 8 through the cylinder-head is held normally closed by a valve which is mounted on a stem, the valve being held upon the port by spring-pressure, and the inlet-pipe

through which the explosive mixture is fed to the cylinder may lead to a gas supply or mixer.

The cylinder 1 has at its end which is adjacent to the cylinder 2 a port 23, which in a modified form may be a series of recesses 24, of a greater length than the width of the piston 10, so that when the pistons 10 and 12 are adjacent to each other the cylinders will be in communication through these recesses or ports to establish between the high-pressure and low-pressure cylinders communication, so that the unexpended force can pass from the high-pressure cylinder to the low-pressure cylinder when the pistons reach the limit of their movement one toward the other at the commencement of the second impulse.

The shaft 16 makes two revolutions to one of the gear-wheel 18, and at a predetermined time fixed by the relative positions of the pistons and cranks with respect to the trip 19 the lever will be actuated to move one of the valves off its seat to open the port leading to the exit-pipe or to establish communication between the high and low pressure cylinders through the port 5 and way 4.

In the arrangement shown the shaft 16 and its pinion 17 make a single revolution for each two strokes of the pistons, the pinion 18 making one complete revolution for each two revolutions of the shaft—for instance, on the first impulse effected by igniting the charge in the high-pressure cylinder the roller or cam is brought in contact with the lever, the cam moving from the points *a* to *b* to engage the lever just prior to the end of the first impulse which brings the pistons near together. When this is effected, the power from the explosive charge passes from the high-pressure cylinder to the low-pressure cylinder through the ports 23, and the cam moving toward the point *c* from the point *b* forces the valve off the seat of the port 5 and permits the valve of the port 6 to close, so that after the high-pressure piston has commenced to move toward the cylinder-head 7 the force from the exploded charge will pass through the port 5, balancing the piston 10 and acting upon the low piston 12, this second impulse forcing the products of combustion out of the high-pressure cylinder into the low-pressure cylinder. When this second impulse has been effected, the cam moves beyond the point *c*, releases the lever, which is thrown by the spring, which opens the exit-port 6 and closes the port 5 between the high-pressure cylinder and way 4.

It will be noted that the lever is only acted upon during a quarter-revolution of the pinion 18 and the cam is so adjusted that almost immediately after the first impulse the cylinders are placed in communication with each other by the opening of the valve for port 5.

When the second impulse is completed, the third movement is effected by the momentum imparted by the first and second impulses, and during the third movement the port 5 is closed and port 6 opened, the high-pressure

piston 10 then drawing in a charge of the explosive mixture as said piston moves toward the end of the cylinder having the port 23 or 70 the ports 24. In the meantime the low-pressure piston moves toward said ports and forces the waste products of combustion out of the cylinder through the port 6, which completes the third movement. The fourth movement is a separation of the pistons, which compresses the charge, which when compressed is ignited to produce the first impulse, as hereinbefore described.

By the construction shown the high and low pressure cylinders are placed in communication as soon as the power-stroke is completed and prior to the movement of any valves, and as soon as the pistons are started on their second impulse they are placed in communication 85 by the opening of a valved port and the closing of a valved exit port, and it will be noted that the valves are only operated during the second impulse, after which they are restored to their normal or initial positions. In this 90 type of engine the high-pressure cylinder is balanced after the first impulse, the engine runs comparatively noiselessly and mufflers are not needed, as the exhaust is at a very low pressure, and the full power of the explosive 95 mixture is utilized, thus insuring economy in operation. Further, the engine is simple in construction and the parts are easily accessible and can be cheaply manufactured.

Fig. 3 shows a modification of the invention, and in said modification instead of providing the high-pressure cylinder with a single port 23 the high-pressure cylinder may have a plurality of recesses or ports 24, which communicate with the way 4 and through 100 said way with the low-pressure cylinder 2. The port 23 or the ports 24 are so positioned that when the piston 10 of the high-pressure cylinder reaches the limit of its stroke toward the low-pressure cylinder the port is 105 opened to admit the charge to the low-pressure cylinder and start the piston thereof on its way toward the piston-head instantaneously, thus giving the valve of the port 5 time to move fully off of its valve-seat. 115*

Having thus described my invention, what I claim as new, and desire to secure by Letters Patent, is—

1. An explosive-engine having a high-pressure cylinder and in line therewith a low-pressure cylinder, the piston-rod of the high-pressure piston passing through the low-pressure piston, a crank-shaft to which the piston-rods are connected so that the pistons will move first toward and then away from one another, 120 a valved port for establishing communication between the cylinders and means for placing the cylinders in direct communication at the end of the first movement or impulse to admit a part of the exploded charge from the 125 high-pressure cylinder into the low-pressure one, for the purpose set forth.

2. An explosive-engine having high and low pressure cylinders arranged in line one with

the other and end for end, pistons for the cylinders, which pistons are actuated to move first toward and then away one from the other, a port for establishing communication between the cylinders when the pistons thereof are adjacent and at the limit of the stroke of the high-pressure piston toward the low-pressure one, and a second port which is opened after the high-pressure piston has passed the first-mentioned port, the second port being held open during the movement of the pistons away from each other, substantially as set forth.

3. In a gas-engine, a high-pressure cylinder and a low-pressure cylinder arranged in line one with the other, a way to one side of the high-pressure-cylinder ports for establishing communication between the cylinders, said cylinders having open ends, in combination with pistons which move toward and then away from one another, each piston being connected to the same shaft, a valve for a port between the way and the high-pressure cylinder, a valved exit-port, and means for operating the valve, substantially as shown and for the purpose set forth.

4. In a compound gas-engine, the combination with a high-pressure cylinder and a low-pressure cylinder and their pistons, the pistons being connected to the cranks of a shaft so that the pistons will move first toward and

then away from each other, of valves and an overrunning port as shown, an exit-valve and a valve for establishing communication between the cylinders, the valves being held over their ports by springs, a lever fulcrumed between the ports and means for actuating the lever, substantially as set forth.

5. A compound gas-engine comprising a double-crank shaft, high and low pressure pistons which operate in cylinders and are connected to the cranks of the shaft so that the pistons will move first toward and then away from one another, a way between the cylinders, a valved entrance-port, a port between the high-pressure cylinder and the way which is overrun by the high-pressure piston, a valved port between the high-pressure cylinder and the way, a valved exit-port, a lever fulcrumed as shown, a gear-wheel on the driven shaft which meshes with a larger gear-wheel, a trip carried by the larger gear-wheel which engages with the lever, substantially as shown and for the purpose set forth.

In testimony whereof I have hereunto set my hand in presence of two subscribing witnesses.

FREDERICK W. TOEDT.
